UNITED STATES PATENT OFFICE.

JOHN C. CROMWELL, OF CLEVELAND, OHIO.

METAL-CASTING APPARATUS.

1,312,164.

Specification of Letters Patent.

Patented Aug. 5, 1919.

Application filed June 15, 1917. Serial No. 174,909.

To all whom it may concern:

Be it known that I, JOHN C. CROMWELL, a citizen of the United States, residing at Cleveland, Cuyahoga county, Ohio, have invented a new and useful Metal-Casting Apparatus, of which the following is a full, clear, and exact description; reference being had to the accompanying drawings, forming part of this specification, in which—

10 Figure 1 is a front elevation of metal casting apparatus embodying my invention.

Fig. 2 is a plan view of a portion of the mechanism shown in Fig. 1, and

15 Fig. 3 is a sectional elevation, partly broken away.

My invention has relation to metal casting apparatus, of the type employed in casting large objects, such as ingots, etc. In the casting of such objects, it is found desirable 20 to use a trough or runner system intermediate the casting ladle and the mold for the purpose of distributing the flowing stream of metal between a plurality of molds.

Heretofore it has been customary to provide 25 means for attaching the trough or runner system to the casting ladle itself; but this is in many respects objectionable for various reasons.

My invention is designed to provide a 30 simple and convenient form of crane mechanism for handling the runners or distributing troughs.

The nature of my invention will be best 35 understood by reference to the accompanying drawings, in which I have shown the preferred embodiment thereof, and which will now be described, it being premised, however, that various changes can be made 40 in the details of construction, arrangement and combination of the various parts without departing from the spirit and scope of my invention as defined in the appended claims.

In these drawings the numeral 2 designates 45 a plurality of ingot molds of any suitable or usual character. 3 designates a casting ladle which is suspended in the usual manner from the hoisting drum 4 of a crane trolley 5 mounted on a bridge 6 arranged 50 to travel on overhead tracks, one of which is shown at 7.

The runner system consists of a main 55 trough or runner 8 which is located directly below the pouring nozzle 9 of the ladle 3, and from which are suspended, as by links 10, the two auxiliary troughs 11. Each of

the troughs 11 is shown as having two bottom discharge openings 12, and each is supplied with metal through discharge openings or nozzles 13 in the main runner 8. This 60 system of troughs or runners for distributing the metal to the several molds 2 has heretofore been used, and forms no part of my invention. Heretofore, however, it has been usual to suspend these runners from the 65 ladle 3. In accordance with my invention, I provide a platform 14 adjacent to the casting station and extending parallel with the line of molds 2. On this platform is mounted a car or carriage 15; and on this 70 car or carriage is pivoted a projecting crane arm 16. Mounted in this arm is a rotary shaft 17, which at its outer end has secured thereto the main runner 8. The shaft 17 can be rotated to tilt the runners by any 75 suitable means, such as the hand lever 18.

The car or carriage 15 is weighted sufficiently to more than counterbalance the weight of the crane 16 and of the runner system carried thereby. For the purpose 80 of moving the car or carriage longitudinally on the platform 14 in correspondence with the travel of the casting ladle 3 over the line of molds, any suitable connection between such carriage and the trolley 5 may 85 be provided. In the drawings I have shown the carriage 15 as having an upwardly projecting member 19 adapted for contact with any suitable depending member 20 of the trolley, these members being so arranged 90 that as the trolley is moved longitudinally the contact of the member 20 with the member 19 will cause the carriage 15 to move with the ladle. At the end of a casting operation the carriage 15 may be moved back 95 to its original position either by hand, or it may be provided with any suitable motive means.

21 designates any usual or suitable stopper actuating mechanism for the ladle 3, 100 and 22 designates handles or levers by means of which the auxiliary runners 11 may be tilted independently of the runner 8 for the purpose of further controlling the flow and distribution of the hot metal.

105 The advantages of my invention will be apparent to those skilled in the art, since it provides runner supporting and operating means which are independent of the casting ladle, and therefore do not require to be connected to and disconnected therefrom with each change in ladles. The mechanism is 110

simple in character and, by causing it to move in unison with the casting ladle, requires no attention on the part of the operator, except that usually required to tilt the 5 runners for controlling the flow and distribution of the hot metal.

I claim:

1. The combination with a movable casting ladle of the bottom-pour type, of a system 10 of runners or troughs, having a plurality of discharges, and a car or carriage upon which said runners or troughs are supported, said car or carriage movable both with and independently of the casting ladle; 15 substantially as described.
2. The combination with a casting ladle of the bottom-pour type, of distributing runners or troughs arranged below the nozzle of the ladle and having a plurality 20 of discharges arranged to simultaneously deliver metal to a plurality of molds, and a

traveling car or carriage supporting and carrying said runners, together with means whereby the car or carriage may be moved in unison with the casting ladle, substantially as described. 25

3. In metal casting apparatus, the combination with a casting ladle of the bottom-pour type, and a crane trolley from which the ladle is suspended, of distributing 30 troughs or runners arranged below the nozzle of the ladle, and a car or carriage having a crane arm which supports and carries the runners, said car or carriage and the trolley having coöperating means whereby 35 the car or carriage may be moved in unison with the crane trolley and ladle, substantially as described.

In testimony whereof, I have hereunto set my hand.

JOHN C. CROMWELL.
